UNITED STATES PATENT OFFICE

PAUL M. CASSAT, OF ABILENE, KANSAS

INTERNAL-COMBUSTION ENGINE

Application filed October 14, 1926. Serial No. 141,583.

The present invention relates to improvements in internal combustion engines, and has for its principal object to provide an internal combustion engine having a firing chamber at the end of each piston.

Another very important feature of the invention lies in the provision of an engine with a structure as indicated above wherein the same may use the four-cycle system of firing.

10 Another very important object of the invention lies in the provision of an internal combustion engine of this nature which is simple and compact in its construction, thoroughly efficient and reliable in its operation, and otherwise well adapted to the purpose for which it is designed.

With the above and numerous other objects in view as will appear as the description proceeds, the invention resides in certain novel features of construction, and in the combination and arrangement of parts hereinafter more fully described and claimed.

In the drawings:—

25 Figure 1 is a vertical section taken through an internal combustion engine embodying the features of my invention.

Figure 2 is a fragmentary side elevation thereof showing the valve operating means, and

30 Figure 3 is a fragmentary top plan view of the cylinder block.

Referring to the drawing in detail, it will be seen 5 denotes the cylinder block which is jacketed in its side walls as is indicated at 6 and 7 in Figure 1. This cylinder block has a plurality of cylinders 8 bored therein in the usual manner and in each cylinder there is 35 slidable a piston P which includes top and bottom heads 9 connected to a spool-like body. The piston heads 9 are provided with suitable piston rings 11. A jacketed head 12 is bolted to the upper surface of the block 5 and a jacketed head 14 is bolted to the bottom side thereof both heads being dished opposite the intake and exhaust pockets. The 40 crank case 15 is bolted to the bottom head 14. The heads 12 and 14 are provided with firing chambers 16 communicating with the cylinders. From the bottom head 9 of each piston

55 P there projects a rigid rod 17 which is slidable through a stuffing box 18 formed in the bottom head 14. A cross head 19 is slidable in a slide-way 20 formed in the crank case 15 and has pivotally engaged therewith a connecting rod 21 which is engaged with one crank of the crank shaft 22. I am describing only one cylinder, and the parts associated therewith in detail, since the others are duplicates thereof and may be easily understood 60 by those skilled in the art.

65 Spark plugs 24 and 25 are mounted in openings of the heads 12 and 14 respectively to fire the charges in the firing chambers 16 at the proper time. Intake poppet valves 27 are associated with the cylinders, two for each cylinder, and one for each firing chamber. Exhaust poppet valves 28 are associated with the cylinders, two for each cylinder, and one for each firing chamber. A cam shaft 30 is rotatable in the block 5 and any suitable means such as is indicated at 31 may be utilized for operating this cam shaft at one-half crank shaft speed as is the common practice in a four cycle engine. On the cam shaft 70 there are disposed cams 33 for operating the exhaust valves and cams 34 for operating the intake valves. An intake manifold is indicated at 35 and communicates with the ports 36 leading into the firing chamber 16 through the intake valve 27 while an exhaust manifold 37 communicates with ports 38 leading into the firing chamber 16 through exhaust valves 28. The exhaust valve in the upper 75 part of the cylinder is located approximately above the intake valve of the lower cylinder and vice versa.

80 From the above detailed description it will be seen that the combustion chambers below the pistons are constructed the same as the ones on top except that an opening is left for the piston rod. When the rod passes through the cylinder head of the lower combustion chamber, the opening is fitted with rings, a stuffing box, or other suitable packing to prevent the compressing from leaking into the crank case. The piston rod is fitted with a guide such as is explained above at the lower 85 end, and the connecting rod is fastened to the 90 end, and the connecting rod is fastened to the 95 end, and the connecting rod is fastened to the 100

cross head forming part of this guide structure somewhat on the order of a steam engine. The water jackets are placed around the lower cylinder head as well as the top. This is an important feature of my invention.

5 The advantages of this type of engine are more power than an engine of the ordinary type with the same number of cylinders, connecting rods, and pistons. This engine with 10 the double acting cylinders would be approximately twice as flexible and powerful as an ordinary engine having the same size and number of cylinders. This engine in a six cylinder could be built less complicated and 15 weigh less than a twelve cylinder ordinary type engine and still have practically the same power. This engine in an automobile could be geared for lower motor speed and still have more power than the ordinary engine. 20 This would mean more speed and power on the road and longer motor life.

From the foregoing, it will be readily apparent that I have provided an efficient and substantial device of the character described, 25 and while the specification manifests in detail the construction of the invention, I do not wish to be understood as limiting myself to the specific details of construction and arrangement of parts as herein described and 30 illustrated, as it is manifest that variations and modifications may be resorted to in the features of construction and arrangement of parts in the adaptation of the engine to various conditions of use without departing from 35 the spirit and scope of the invention. I therefore reserve the right to all such variations, modifications as properly fall within the scope of my invention, as hereinafter claimed. From the foregoing, it is thought 40 that the construction of my invention will be clearly understood and, therefore, a more extended explanation has been omitted.

Having thus described the invention, what I claim as new and desire to secure by Letters 45 Patent is:—

In an internal combustion engine construction comprising a base, a block detachably secured upon said base, and a head detachably secured upon said block, said block having 50 a cylinder bore therethrough and intake and exhaust pockets at each end thereof, the opposed sides of the base and head being dished for communicating said pockets and cylinder bore.

55 In testimony whereof I affix my signature.
PAUL M. CASSAT.
